UNITED STATES PATENT OFFICE.

EDWARD J. WILLING, OF HATTON, SASKATCHEWAN, CANADA.

BUNDLE-CARRIER GUARD.

Application filed June 7, 1924. Serial No. 718,606.

This invention relates to improvements in binding machines and has for an object the provision of a guard for preventing bundles of grain from accidentally falling from the bundle carrier of the machine between dumping points, so that the operation of binding grain will be facilitated and the time and labor necessary materially reduced.

Another object of the invention is the provision of a guard for the above purpose which may be readily attached to a binding machine so as to properly center the bundled grain irrespective of whether the machine is adjusted for long or short grain.

Another object of the invention is the provision of a guard which is capable of being swung to an inactive position to permit of passing through narrow spaces and which when secured in position for use, will provide a brace bar for the binding machine stripper frame.

With the above and other objects in view, the invention further includes the following novel features and details of construction, to be hereinafter more fully described, illustrated in the accompanying drawings and pointed out in the appended claims.

In the drawings:—

Figure 1 is a fragmentary view partly in section showing the invention in position for use.

Figure 2 is an enlarged fragmentary perspective view illustrating the connection between the inner end of the guard and the ejector shaft housing.

Figure 3 is a fragmentary top plan view illustrating the manner of connecting the guard to the stripper frame.

Figure 4 is a section on the line 4—4 of Figure 3.

Referring to the drawings in detail wherein like characters of reference denote corresponding parts, the invention is shown as applied to a portion of a binding machine for which it is adapted. For this purpose the bundle carrier is shown at 10, a portion of the deck of the binding machine at 11, the ejector shaft at 12 and the ejector shaft housing at 13, while the stripper frame is shown at 14.

The invention which provides a guard that extends over the bundle carrier comprises an arm 15 having one end pivotally secured to the ejector shaft housing 13 and its opposite end arranged in juxtaposition to the outer edge of the bundle carrier 10, so that

the arm 15 will extend transversely across the bundle carrier and prevent the bundles from accidentally falling off the carrier. In addition, the position of the guard will act to center the bundles as it will remain in position irrespective of whether the machine is adjustable for short or long grain.

As stated, the arm 15 or guard is pivotally mounted upon the ejector shaft housing 13 and for this purpose its inner end extends through and is secured within the usual eye or lug 16 which is carried by the housing 13 and within which the stripper frame brace bar is usually secured. Any suitable means may be provided for holding the inner end of the guard or arm 15 in place, the means illustrated consisting of a cotter pin 17.

Spaced from the inner end of the guard there is provided an open loop 18 which is adapted to receive the outer end of the stripper frame 14, while a U-shaped clamp 19 extends around this loop and beneath the frame 14 and acts to hold the guard and frame together. By this means the guard 15 is properly supported above the bundle carrier and at the same time, the guard acts to brace the stripper frame 14 so that the usual brace rod may be dispensed with. The clamp 19 is provided at its ends with eyes or hooks for the reception of a pin 20 and the latter may be removably secured in place by means of a cotter pin 21, so that the guard and frame 14 may be disconnected and the former swung inward to the dotted line position shown in Figure 1 of the drawings so as to be out of the way and permit of the passage of the machine through narrow places.

The invention is susceptible of various changes in its form, proportions and minor details of construction and the right is herein reserved to make such changes as properly fall within the scope of the appended claims.

Having described the invention what is claimed is:—

1. In combination with the bundle carrier of a binding machine, a guard comprising a curved member adapted to extend transversely across the bundle carrier above the latter with one end located adjacent the outer end of the carrier, means for pivotally securing the other end of the guard to the ejector shaft housing of the binding machine and means for removably securing the guard to the binding machine stripper frame.

to hold the guard in active position and to provide a stripper frame brace.

2. In a bundle carrier, the combination with a binding machine stripper frame, of a guard having its inner end secured to the ejector shaft housing of the binding machine and its outer curved end normally located adjacent the outer edge of the carrier,

an open loop portion provided within the guard to receive the stripper frame and means to secure said guard to said frame to brace the frame and hold the guard in position.

In testimony whereof I affix my signature.

EDWARD J. WILLING.
